UNITED STATES PATENT OFFICE.

LOUIS COBBAERT, OF NINOVE, BELGIUM.

MATCH-MAKING MACHINE.

No. 804,383.

Specification of Letters Patent.

Patented Nov. 14, 1905.

Application filed August 13, 1901. Serial No. 71,930.

To all whom it may concern:

Be it known that I, LOUIS COBBAERT, manufacturer, a subject of the King of Belgium, residing at Ninove, in the Kingdom of Belgium, have invented new and useful Improvements in or Relating to Match-Making Machines, of which the following is a full, clear, and exact description.

The present invention relates to the match-making machines of that kind in which the match sticks or splints are held from the beginning in frames, which follow each other without interruption, passing through all the necessary operations, being taken out of the frames only at the end of the operation to be directly distributed or packed in boxes.

The object of this invention is to provide an improved means of immersing the end of the matches and an improved means for conveying the matches through the drying-chamber.

Other objects or advantages will appear in the following description, and will be particularly pointed out in the claims.

In the drawings, Figure 1 represents a side view of the head-dipping apparatus and a portion of the drying-chamber. Fig. 1^a represents the remaining portion of the drying-chamber. Fig. 2 is a front view of the match-dipping apparatus. Fig. 3 is a front view of the first frame-raiser.

A frame *c*, traveling on an endless band *X* and carrying the match-splints which have been dipped in paraffin by any suitable means, is submitted to the action of a mechanism the object of which is to well immerse the ends of the match-splints into the chemical ignition-paste distributed on the endless band. This mechanism consists of a plate *p*, held above the splint-frame *c* on four sliding rods controlled by a spring *p'*, the lower ends of which rods are connected to slide cross-bars *t*, provided in the central part with rollers *g'*, moving in the corresponding groove of a cam or eccentric *p*², actuated by bevel-gearing *p*³ in such a manner that the plate *p* descends at the required moment onto the frame *c*, and thereby forces the ends of the match-splints to press into and through the ignition-paste until they touch the band. The rods are controlled by springs which tend to raise the plate *p* after the roller *g'* has passed out of the downward deflection of the cam-groove, thereby causing the ascent and release of the frame, which has been carried forward on the band, at the next intermittent movement of the

latter to an intermittently-moving elevator, which is arranged in front of the drying-chamber and is adapted to present the frames in succession at the entrance to the drying-chamber, in which they are moved successively upward and backward and forward by means of a second elevation arrangement coöperating with the first and arranged at the other end or side of the drying-chamber and two drivers *x*², having alternate horizontal movements. This first elevator comprises four vertically-movable uprights *r*¹ *r*¹, arranged in a framework of the machine with means for imparting to it an intermittent ascending and descending movement—for instance, by an eccentric cam *r*², actuated by bevel-gearing *r*³, said cam being provided with a groove in which rollers *g*' on sliding cross-bars *t*', to which the uprights *r*¹ *r*¹ are attached, each of these bars in the present case being actuated by a similar eccentric mechanism *r*² *r*³, as represented in Fig. 1. This is done to meet strain and weight of the great number of frames received by the elevator. At the lower part and inner side the uprights *r*¹ *r*¹ are provided with a set of clips *r* *r*—four in the present example—which are controlled by or act as springs in such a manner that normally they project forward, while they can be pressed back into or against the body of the uprights under the influence of pressure exercised against their edges by the frames *c*, as will be explained hereinafter. By the side of the three upper spring-clips are arranged in stationary uprights two sets of three similar clips *r*⁴ *r*⁴, coöperating with the former, and finally movable uprights *r*' *r*' are provided in their upper parts with a series of fixed slide-ways or grooves *x*² *x*² on each side. This elevator device, which acts to raise the frames, is immediately followed by the drying-chamber, which consists of a rectangular chamber *x*, the length and height of which depends on the desired length of the passage of the frames to the chamber, so as to insure a perfect drying of the heads of the match under the influence of a current of hot air produced in or passing through said chamber *x* by means of a blast device or the like, which, however, is not represented in the drawings and need not be described, since it does not form an integral part of the invention. In the interior of the said drying-chamber *x* on the inner longitudinal walls thereof are provided, say, nine sets of slide-ways *x*', similar to the slide-ways *x*² of the elevator and extending from one end

of the drying-chamber to the other and represented in the drawings in Figs. 1 and 1^a as broken into two parts. Both at the entrance and at the outlet of the drying-chamber are arranged guides or angle-pieces x^4 , close below the slideways x' , being intended to regulate exactly the position of the various frames when entering the slideways, as will be described hereinafter. At the other end of the drying-chamber x is arranged an elevator similar to the one at the entrance; but this elevator is not provided with clips $r^4 r^4$ and is provided in this example with only seven slides r^2 instead of eight. In front of each elevator is arranged a propelling plate or driver x^3 —i. e., one on the left-hand side of one elevator, the other on the right-hand side of the other smaller driver in front of six slides. The driver consists of a vertical surface so arranged that it can actuate all the slides at one time. The propeller-drivers x^3 are given a horizontal reciprocating movement, one moving forward, while the other recedes, following the same intermittent motion as the endless band X, which transfers one frame at a time to the elevator, the intermittent movement being effected by mechanism consisting of a loop-rack and toothed wheel device B', as shown in the drawings.

The length of this alternating reciprocating movement of the drivers x^3 corresponds to the length of movement of the frames in the elevator and drying-chamber, and in order to insure constant precision the drivers x^3 , which are less broad than the elevators, in order to be able to pass between the uprights and the slideways, are guided horizontally both at the top and bottom by long slides g , which in their turn are guided in the framework of the machine.

The transfer of the match-splint frames from the endless band X to the first elevator and their movement through the drying-chamber x is effected in the following manner:

At the moment when the endless band X has brought the match-frame c between the elevator-uprights $r^4 r^4$ the elevator occupies the lowest position and the spring-clips $r^4 r^4$ are below the edges of the match-frame, as represented in Figs. 1 and 3. The cam r^2 in its continuous rotation raises the elevator and with it the match-frame c. During this ascent the edges of the match-frame will press outward the stationary pawls $r^4 r^4$, which spring back again as soon as the match-frame has passed beyond them, and will then support the frame in stationary position while the elevator descends again to raise the second match-frame, which, in the meantime, has been placed in position by the endless band X. During this downward movement, the elevator-clips $r^4 r^4$ recede and slide by the edges of the two match-frames and project again at the end of the downward movement and are ready to raise the two frames together in one lift and

to place them on the corresponding next pair of stationary clips $r^4 r^4$ as soon as the first frame has arrived on the last set of clips, which is on a level with the first pair of slideways x' of the drying-chamber. At this moment the driver x^3 on the left advances toward the right and pushes the match-frames forward into the slideways x' of the drying-chamber, and as on the next movement of the propeller toward the right a second match-frame has been placed on the upper clips in front of the same slideways the propeller pushes this second match-frame into the drying-chamber, which frame pushes the first match-frame forward in front of it, and so on until the lowest set of the slideways of the drying-chamber have received the full number of frames corresponding to the length of the drying-chamber. The next movement toward the right of the driver x^3 on the left side will cause the first frame to enter into the lowest slideways x' of the elevator at the other or right side of the drying-chamber. This elevator at that moment occupies the lowest position, and in this position the right driver x^3 being shorter than the left one cannot interfere with this frame. The right elevator raises the frame from its lowest position to the next higher one, so as to place it in front of the second set of slideways x' of the drying-chamber. In this position the right driver on its movement toward the left will push this match-frame into the drying-chamber by entering it into the corresponding slideways x' . It is to be understood that the moving of the two drivers is reciprocal and alternative from the left to the right. The following frames as they arrive push it again forward into the lower slideways of the first elevator, which then places it by its own ascending movement in front of the third set of slideways of the drying-chamber, into which it is then introduced. This combined upward and backward and forward movement is continued until all the sets of slides of the drying-chamber are charged with the frames moving intermittently, the sets marked by the uneven number steadily traveling toward the right, while those of the even numbers travel similarly toward the left in such a manner that each frame carrying the tipped matches passes, say, as in the present case, nine times through the entire length of the drying-chamber—i. e., from the time of first entering into the chamber at the bottom on the left-hand side until it leaves it at the top on the right of the chamber, where it occupies the last set of slides which pass above the right-hand elevator and where the match-frames are received by a workman.

Having thus described my invention, what I claim as new, and desire to secure by Letters Patent of the United States, is—

1. In a machine of the class described, the combination with the drying-chamber, and a splint-carrying frame, of horizontal slideways

arranged within the chamber, one above the other in parallel relation, and means for shifting the splint-carrying frame from one slideway to another.

5 2. In a machine of the class described, the combination with a drying-chamber, and a splint-carrying frame, of horizontal slideways arranged within the chamber, one above the other in parallel relation, and means at the 10 ends of the slideways for shifting a frame from one slideway to a slideway next to it.

3. In a machine of the class described, the combination with a drying-chamber, and a splint-carrying frame, of horizontal slideways 15 arranged within the chamber, one above the other in parallel relation, and elevators at each end of the slideways.

4. In a machine of the class described, the combination with a drying-chamber, and a splint-carrying frame, of horizontal slideways 20 arranged within the chamber, one above the other in parallel relation, elevators at each end of the slideways, and means for shifting the splint-carrying frames onto and from the 25 elevators.

5. In a machine of the class described, the combination with a drying-chamber, and a splint-carrying frame, of horizontal slideways 30 arranged within the chamber, one above the other in parallel relation, elevators at each end of the slideways, drivers arranged on the sides of the elevators, and means operating the drivers to shift the splint-carrying frame.

6. In a machine of the class described, the combination with a drying-chamber, and a splint-carrying frame, of horizontal slideways 35 arranged within the chamber, one above the other in parallel relation, elevators at each end of the slideways, comprising a plurality 40 of uprights, means on the uprights for receiving the splint-carrying frames, and means for causing an intermittent ascending and descending movement of the uprights.

7. In a machine of the class described, the

combination with a drying-chamber, and a 45 splint-carrying frame, of slideways arranged within the chamber, one above the other, elevators at each end of the slideways, comprising a plurality of uprights, means on the uprights for receiving the splint-carrying 50 frames, means for causing an intermittent ascending and descending movement of the uprights, one of said elevators being provided with spring-clips, and spring-clips carried by the drying-chamber, and coöperating with the 55 spring-clips on one of the elevators to deliver the splint-carrying frame into the drying-chamber.

8. In a machine of the class described, the combination with a drying-chamber, and a 60 splint-carrying frame, of horizontal slideways arranged within the chamber, one above the other in parallel relation, elevators at each end of the slideways, and means for causing an intermittent ascending and descending 65 movement to the elevator.

9. In a machine of the class described, the combination with a drying-chamber, and a splint-carrying frame, of horizontal slideways 70 arranged within the chamber, one above the other in parallel relation, elevators at each end of the slideways, means for causing an intermittent ascending and descending movement to the elevator, spring-clips carried by the drying-chamber, spring-clips carried by 75 one of the elevators and coöperating with the clips of the drying-chamber to deliver the splint-carrying frame into the drying-chamber; and drivers on one side of each elevator, to move the splint-frames from the elevators 80 to the slideways in the drying-chamber.

In witness whereof I have hereunto set my hand in presence of two witnesses.

LOUIS COBBAERT.
